UNITED STATES PATENT OFFICE.

PETER N. MOORE, OF MILWAUKEE, WISCONSIN.

FRICITION SPRING DRAFT-RIGGING FOR RAILWAY-CARS.

SPECIFICATION forming part of Letters Patent No. 782,793, dated February 14, 1905.

Application filed September 8, 1904. Serial No. 223,719.

To all whom it may concern:

Be it known that I, PETER N. MOORE, a citizen of the United States, residing in Milwaukee, in the county of Milwaukee and State of Wisconsin, have invented a new and useful Improvement in Friction Spring Draft-Rigging for Railway-Cars, of which the following is a specification.

My invention relates to improvements in friction spring draft-rigging for railway-cars.

The object of my invention is to provide a friction spring draft-rigging of a simple, strong, efficient, and durable construction capable of exerting a great frictional resistance in connection with a direct-acting spring resistance arranged in the line of draft.

My invention consists in the means I employ to practically accomplish this object or result—that is to say, it consists, in connection with the draw-bar, draw-bar extension or strap, side plates or stop-castings, followers, and a longitudinally-arranged spring, of two pair of friction-clamps, each pair having inclined friction-surfaces between which an inclined friction member may be moved and a pair of longitudinally and transversely movable friction-slides, each having inclined friction-faces adapted to frictionally engage and slide between the inclined friction-faces of the friction-clamps.

My invention also consists in the novel construction of parts and devices and in the novel combinations of parts and devices herein shown or described.

In the accompanying drawings, forming a part of this specification, Figure 1 is a central vertical longitudinal section of a friction spring draft-rigging embodying my invention. Fig. 2 is a horizontal section. Fig. 3 is a partial cross-section on line 3-3 of Fig. 2. Fig. 4 is a detail perspective view of one of the longitudinal and transversely movable friction-slides, and Fig. 5 is a detail perspective view of one of the friction-clamps.

In the drawings, A represents the draft or center sills of a car; A', the front or cross sill; C, the coupler; B, the draw-bar; and B', the draw-bar extension or strap, secured to the draw-bar by bolts or rivets b.

D D are the side plates or stop-castings,

having front stops d and rear stops d' for the followers E E' to abut against and integral upper guides d² and lower guides d³ for the followers to reciprocate on or between, the lower guides being in the form of removable plates secured in place by bolts d⁴ to permit the ready insertion and removal of the draft-rigging.

F is a longitudinally-arranged spring directly behind the draw-bar in the line of draft and having a small spring f nesting within it.

G G' and G' G' are two pair of friction-clamps having oppositely-inclined friction-faces g g', between which co-operating friction members may slide. The friction-clamp G abuts against one of the followers and the friction-clamp G' against one end of the spring F. One pair of friction-clamps is thus interposed between the spring and each follower.

H H are two longitudinally and transversely movable friction-slides, each having two inclined friction members or wings h, adapted to reciprocate between and frictionally engage the inclined friction-faces g g' of the two pair of friction-clamps G G'. The longitudinally and transversely movable friction-slides H H are each preferably of a semi-box shape with inclined ends, formed by the inclined friction members h h or furnished with integral sides h' h' to give strength to the friction-slide as a whole or brace and support its oppositely-inclined friction members h h. To guide and register the transversely and longitudinally movable friction-slides H H with each other in their transversely-reciprocating movement, these friction-slides are provided or preferably provided with interengaging transverse guides h² h³, the guides h² on the one slide H fitting between the guides h³ on the other slide H, as will be readily understood from the drawings. These interengaging transverse guides on the friction-slides H H not only guide the friction-slides in their transverse reciprocation in respect to each other, but also cause both friction-slides H H to reciprocate longitudinally together or in unison with each other as the draw-bar moves back and forth.

The two friction-clamps G' G', which abut directly against opposite ends of the spring

F, are preferably provided with lugs h^4 to center the spring or hold it in place.

As the transversely and longitudinally movable friction-slides H H move between the parallel inclined friction-faces $g g'$ of the friction-clamps G G' their inclined friction members h are forced into close frictional engagement with and clamped between the friction-clamps, and thus exert very powerful frictional resistance.

The operation is as follows: In buffing, the front follower E and front pair of friction-clamps G G' move with the draw-bar, while the rear follower and rear pair of friction-clamps are held stationary by the rear stops on the side plates or stop-castings D, while at the same time the friction-slides H H are caused to move both transversely in respect to the draw-bar and also longitudinally, thus causing the inclined friction members $h h$ of the friction-slides H to frictionally slide or reciprocate between the inclined friction-surfaces $g g'$ of the friction-clamps G G'. In pulling, the operation is the same, but the reverse, the front follower and front pair of friction-clamps being now held stationary, while the rear follower and rear pair of friction-clamps move with the draw-bar.

I claim—

30 1. In a friction spring draft-rigging, the combination with the draw-bar, draw-bar strap or extension, longitudinally-arranged spring, followers and side plates or stop-castings, of two pair of friction-clamps, one pair 35 between each follower and the spring, and each friction-clamp of each pair having oppositely-inclined friction-faces and a pair of transversely and longitudinally movable friction-slides, each having inclined friction mem-

bers reciprocating between the parallel friction-faces of the friction-clamps, and said friction-slides being provided with interengaging guides to guide the transversely-reciprocating movement of said slides in respect to each other, and to cause the two slides to move 45 together longitudinally, substantially as specified.

2. In a friction spring draft-rigging, the combination with a longitudinally-arranged spring and followers, of two pair of friction-clamps having inclined friction-faces and two longitudinally and transversely movable friction-slides having inclined friction members longitudinally engaging the inclined friction-faces of the friction-clamps, said friction-slides 55 having interengaging guides to cause them to move together longitudinally and to guide their transverse reciprocation in respect to each other, substantially as specified.

3. In a friction spring draft-rigging, the combination with a longitudinally-arranged spring and followers, of a pair of friction-clamps between one end of the spring and one of the followers, each of said clamps having oppositely-inclined friction-faces and two longitudinally and transversely movable friction-slides having each an inclined friction member frictionally engaging the inclined friction-faces of said friction-clamps, said friction-slides having transversely-extending interengaging guides to cause said slides to move together longitudinally and to guide their transverse reciprocation in respect to each other, substantially as specified.

PETER N. MOORE.
